UNITED STATES PATENT OFFICE.

HERMAN C. BOEDICKER, OF MINNEAPOLIS, MINNESOTA.

PHOTOLITHO MACHINE.

Application filed April 26, 1919. Serial No. 292,980.

To all whom it may concern:

Be it known that I, HERMAN C. BOEDICKER, a citizen of the United States, and a resident of Minneapolis, in the county of 5 Hennepin and State of Minnesota, have invented certain new and useful Improvements in Photolitho Machines, of which the following is a specification.

This invention relates to a photolithograph machine, and relates specifically to improvements on the devices shown in my copending applications, Serial No. 56931, filed October 20, 1915, and entitled "Art of making photo prints on printing plates"; 10 and Serial No. 150,613, filed February 23, 1917, (patented January 13, 1920, No. 1,327,752, for combination machine for making photo-prints on printing plates by direct contact or projection printing).

20 One object of my invention is to provide, in a photolithograph machine, improved means for obtaining the relative adjustment of the projection machine and printing plate.

25 Another object is to provide improved means for locating and relocating the projection machine with respect to the printing plate device.

30 Another object is to provide means for bringing the negative into direct contact with the printing plate when making contact prints, the contact being under a certain pressure, releasing and readjusting the negative, and bringing it back against the printing plate.

35 Another object is to provide an adjustable pressure beam for the printing plate, improved means for clamping the printing plate so it is drawn across the pressure beam, and individual means for taking buckles out of the plate.

40 Another object is to provide an improved form of cushion padding for the pressure beam.

45 Another object is to provide improved means for holding the negative holder, when it is under pressure, against the printing plate and pressure beam and, at the same time, allow for expansion of the double camera bed plate.

50 Another object is to provide means for joining the frame, carrying the projection machine, the printing plate and the printing plate pressure beam supporting means into practically a unitary structure when a print is being made by direct contact.

Another object is to provide improved means for supporting the negative so it will withstand the pressure applied thereto against the printing plate pressure beam, 60 and provide means for indicating such pressure.

Another object is to provide improved means for centralizing the negative at any desired point and at any desired angle. 65

Another object is to provide improved means for daylight working of the machine, whether used for direct contact or projection printing.

With these and incidental objects in view, the invention consists of certain novel features of construction and combination of parts, the essential elements of which are hereinafter described with reference to the drawings which accompany and form a part 75 of this specification.

In the drawings, Fig. 1 is a perspective view of my improved machine as used for projection printing. Fig. 2 is a side elevation of the front end of the machine as 80 used for contact printing. Fig. 3 is a fragmentary sectional detail of the means used for moving the carriage longitudinally. Fig. 4 is an end view of the same. Fig. 5 is a fragmentary sectional detail showing 85 the adjustable rollers on which the carriage rides. Fig. 6 is an end view of the same. Fig. 7 is a fragmentary sectional view showing the means for locking together the carriage and the contact pressure beam structure. Fig. 8 is an end view of the same.

Fig. 9 is a fragmentary side elevation detail of the scale and pointer for locating the position of the screen frame. Fig. 10 is a sectional bottom view of the same. Fig. 95 11 is a fragmentary sectional detail showing the means for operating the split nut controlling the longitudinal motion of the carriage. Fig. 12 is an enlarged detail of the split nut and its operating eccentrics, and 100 Fig. 13 is a partly sectional plan view of the same as positioned in its housing.

Fig. 14 is a side elevation of one style of negative box. Fig. 15 is a similar view of a second style of negative box. Fig. 105 16 is a fragmentary plan view of the sliding ways carried on the top of the table, and the supporting and telescoping feet for the bellows support and negative holder. Fig. 17 is a sectional plan view of the same 110 and showing the operating means for obtaining pressure contact between the nega-

tive and printing plate. Fig. 18 is an enlarged sectional detail of one of the eccentrics used in moving the sliding table longitudinally for pressure contact.

- Fig. 19 is a sectional side view, taken from the rear, of the means used for raising and lowering the screen frame. Fig. 20 is a sectional plan view of the same. Fig. 21 is a section taken on the line 21—21, Fig. 19. Fig. 22 is a fragmentary sectional detail taken on the line 22—22, Fig. 19. Fig. 23 is a sectional rear view of the means for raising and lowering the contact beam. Fig. 24 is a fragmentary sectional view of one of the raising and lowering nuts and screws. Fig. 25 is a sectional rear view of the means used for raising and lowering the upper clamp beam in the screen frame. Fig. 26 is a section taken on the line 26—26, Fig. 25. Fig. 27 is a front view of the beam showing the means for turning the bevel gear. Fig. 28 is a fragmentary section taken on the line 28—28, Fig. 1. Fig. 29 is a section taken on the line 29—29, Fig. 1. Fig. 30 is a fragmentary front view of a portion of the upper clamp beam showing one of the individual clamps and a fragment of a negative plate clamped thereto. Fig. 31 is a fragmentary rear view showing the hinge of the individual clamp.

Fig. 32 is an enlarged detail of the end locking means provided for the registering scale. Fig. 33 is a side view of the same. Fig. 34 is a fragmentary sectional detail of the beam supporting the front end of the lower half of the camera bed plate and showing the adjustment means for taking up wear in its sliding way.

- Fig. 35 is an enlarged detail of the front corner of the portion of the carriage at which the traveling tape is registered with respect to the scale carried by the carriage. Fig. 36 is a partial sectional view of the same, showing the manner in which the tape is passed transversely across the carriage.

Fig. 37 is an enlarged detail showing the means for raising and lowering the lamp support. Fig. 38 is a sectional view taken on the line 38—38, Fig. 37; and Fig. 39 is a section taken on the line 39—39, Fig. 37.

- Fig. 40 is a partial sectional plan view of the rear corner of the carriage on the operating side of the machine, showing the manner in which the tape passes transversely across the carriage at that end. Fig. 41 is an enlarged sectional detail showing the supporting means for the pulley around which the tape passes at the opposite corner. Fig. 42 is a view taken at right angles to that shown in Fig. 41. Fig. 43 is a sectional detail showing the manner of making angular adjustments on the negative holder. Fig. 44 is an enlarged detail showing the micrometer for registering the angular adjustment effected by the means shown in Fig. 43.

Fig. 45 is a section taken on the line 45—45, Fig. 43.

Fig. 46 is a detail of the vertical adjustment of the negative holder. Fig. 47 is a section taken on the line 47—47, Fig. 46. Fig. 48 is a detail showing the transverse adjustment of the negative holder.

Fig. 49 is a detail showing the level and protractor used in lining up a negative. Fig. 50 is a side view of the same. Fig. 51 is a partial section taken on the line 51—51, Fig. 49, and Fig. 52 is a sectional view taken on the line 52—52, Fig. 49.

Fig. 53 Sheet 5, is a sectional detail showing the manner in which the pressure beam slides in its ways.

Fig. 54 is a fragmentary view showing the manner in which the side curtains are mounted to the screen frame and the top and bottom curtains.

Fig. 55 is a similar view showing the manner in which the top and bottom curtains are attached to the rollers and screen frame.

Fig. 56 Sheet 8 is a similar view showing the manner in which the side curtains are attached to the bellows when the machine is used for contact printing, and Fig. 57 is a fragmentary view showing the manner in which the side curtains are slidably attached to the bellows for projection printing.

Fig. 58 is a front view of the negative holder, and Fig. 59 is a section taken on the line 60—60, Fig. 58, and showing a portion of the negative holder mounting frame, Figure 60 is a fragmentary detail showing the anti-friction mounting of the side curtains, and Figure 61 Sheet 4 is a fragmentary perspective detail of the contact pressure indicating device.

Relative adjustment of projection machine and printing plate.

As shown in Fig. 1, the sub-base 1 is mounted on springs or vibration absorbing means 2, so that this sub-base, together with what is carried thereon, will act as a unit in regard to any vibrations transmitted to the sub-base from the earth or building in which the machine is placed.

A carriage 3, mounted on rollers 4, runs longitudinally on the sub-base 1 on the tracks 5, Figs. 1 and 5.

The rollers 4 are carried by the fork 6, and each arm of the fork has a threaded bushing 7 in which is journalled the roller shaft 8, so that, by screwing the two bushings in or out by means of the heads 9, the rollers 4 may be adjusted laterally so as to run accurately on the tracks 5 and provide means for taking up wear. As shown particularly in Figure 5, the sides of each track-way converge upwardly and are connected at the top of the track or rail by a flat wall. The rollers have diverging side walls which

fit and ride upon the converging side walls of the tracks with the central part of the periphery of the roller spaced from the upper wall of the track.

5 The carriage 3 may be moved longitudinally by means of the hand wheel 10, Fig. 1, which rotates the shaft 11, Fig. 3, journalled in a portion of the carriage frame, and, by means of the bevel gears 12 and 10 spur gears 13, 14 and 15, rotates the screw 16.

The screw 16, Figs. 11, 12 and 13, cooperates with the split nut comprised of halves 17 and 18, controlled as hereinafter described, and this split nut is carried in the housing 19, rigidly attached to the sub-base 1, hence, when the screw 16 is rotated, the carriage 3 will travel back and forth on the tracks 5.

20 Journalled in the housing 19, the shafts 20 and 21 carry eccentrics 22 and 23, respectively, playing in the apertures provided therefor in the halves 17 and 18 of the split nut.

25 The shafts 20 and 21 have crank arms 23' and 24, respectively, connected by a link 25, and a link 26, hinged at 27 to the crank 23'. is hinged at 28 to the rod 29, which, in turn, is pivotally and slidably joined at 30 to the lever 31, hinged at 32 to the frame of the sub-base.

It is evident that, with the lever standing in the position as shown in Fig. 11, and the split nut thus opened, the screw 16 is 35 free and the carriage 3 may be easily rolled back and forth by hand for a quick, coarse positioning of the carriage.

By throwing the lever 31 clockwise from the position shown in Fig. 11, the split nut 40 is closed onto the screw 16 and the carriage is then under control of the hand wheel 10.

The camera bed plate 33, Fig. 1, is mounted on the carriage 3 for slidable transverse movement thereon, and this movement is 45 controlled by the hand wheel 34, which turns the screw 35 and, through bevel gears 36 and shaft 37 and bevel gears 38, also turns the screw 39. These screws 35 and 39 co-operate with nuts 40 and 41, respectively, carried by 50 the bed plate 33, and, through the engagement of the screws and nuts, bed plate 33 is moved transversely by the operation of the hand wheel 34. Substantially the same mechanism is shown in my Patent No. 55 1,327,752 above referred to.

The forward end of the bed plate slides in the carriage 3 in a dovetailed way 42 in said carriage, Fig. 2, while the rear end rests on a flat way 43 at the rear end of the carriage 3, and the flat way 43' near the center of the bed plate.

The construction and operation just described provides for the longitudinal and transverse movement of the devices carried 60 by the bed plate 33, whether the machine is

used for contact printing or projection printing. Vertical adjustment between the devices carried on the bed plate 33 and the printing plate on which print is being made is provided by the vertical movement of the printing plate, itself.

Supported by the braces 44, Fig. 1, is a screen frame guide comprised of upright beams 45 and 46 tied together by the transverse beam 47. Mounted for vertical slide- 75 able movement therein is a screen frame comprised of a top member 48, side members 49 and 50, and frame clamp bar 51.

A hand wheel 52, Figs. 1, 19 and 20, provides means for turning the shaft 53, and, through spiral gears 54, Fig. 20, the screw 55.

Co-operating with the screw 55 is a nut 56 carried by the screen frame, and a similar nut 56' is controlled, through the screw 55' and the spiral gears 54', by the shaft 53. Hence the operation of the hand wheel 52 raises or lowers the screen frame, the side members 49 and 50 traveling in ways in the upright beams 45 and 46, as shown in 90 Fig. 20.

The side portions of the upright beams 45 and 46, which are bolted at 127, Fig. 53, to the adjacent portions 128 of the braces 44, are channelled out as shown at 129, and the pressure beam 59, Figs. 1, 2 and 23 and 53, has tongues 60 and 61 Fig. 23 slidably mounted therein.

Referring to Figs. 23 and 24, both of which are arranged horizontally to accommodate themselves to the drawing sight, but which in point of fact show vertically arranged parts, there are shown screws 62 and 63, journalled at 130 and 131 at their upper ends, that is to say, the left-hand side of the views, and at 132 and 133 at their lower ends, that is to say, at the right-hand side of the views, co-operate with the flanged nuts 64 and 65, respectively, carried by the pressure beam 59, and these screws are controlled by the hand wheel 66 through the shaft 67 and spiral gears 68 and 69, so the rotation of the hand wheel 66 will raise and lower the pressure beam 59 in the ways 129 independently of the screen frame.

In my standardized machine the negative glass is eighteen inches square, but a negative film of a smaller area may be centrally located on this glass. Hence, when prints are being made along the lower horizontal portion of a printing plate, the beam 59 should be moved downward so as to give a good pressure surface for the negative glass, and, similarly, the contact pressure beam may require readjustment when the upper horizontal portion of a printing plate is having prints made thereon.

In the standardized machine, the pressure beam 59 is eighteen inches wide so that, normally, the entire area of the negative glass 130

is supported by this beam, the printing plate being moved vertically upward or downward across the face of the beam by the movement of the screen frame already described.

Locating and relocating in step and repeat photo printing.

In color work, one negative is prepared for each color that is to be printed, and whether a printing plate is to have a single print made thereon and corresponding plates for each of the other negatives prepared for the color printing, or whether each of the negatives is to be produced in multiplicity of prints on each plate to facilitate quantity printing, it will be obvious that great accuracy will be required of the photo printing machine.

As the colors must register exactly when printed, extreme accuracy is demanded, and, for commercial operation of a photo-lithograph machine, this accurate handling of the machine should also be rapid.

Whether used in contact printing or projection printing, it is evident that registrations will be similar, and hence a description of the locating and relocating means will be carried through for a set of contact printing operations.

With the carriage in the position shown in Fig. 2, the negative 70 is brought into contact with the printing plate 71 by the operation of the hand wheel 10 under considerable pressure and the print made in a manner well known to those skilled in the art. The negative is then moved backwardly from the printing plate about three quarters of an inch by special means hereinafter described, and the camera bed plate moved transversely on the carriage by turning the hand wheel 34 so as to bring the negative into the position for the next print in the same horizontal line as the one first made.

When the first print is made, a reading is taken of the registration of the arrow 72 on the tape 73, Fig. 35, with the scale 73' on the carriage, and a record made of this reading.

A record is also taken of the reading of the micrometer 74, Fig. 2, and the cyclometer 75, the tape giving the approximate location so that the negative may be relocated approximately by watching the tape 73 while turning the hand wheel 34 and the exact location made by the reading of the cyclometer, which makes one step every time the hand wheel 34 is rotated once, and the micrometer, which is divided into two-hundred-fifty graduations.

As the screws 35 and 39 are of four threads to the inch, each graduation of the micrometer corresponds to a transverse movement of one one-thousandth of an inch of the negative, and, as the dial of the micrometer is

made of such dimension that the distance between graduations is approximately a quarter of an inch, it is a simple matter to read the location or relocation of the negative to within less than one one-thousandth of an inch.

The tape 73 is rigidly mounted at one end of an angle bracket 76, Figs. 32 and 33, mounted on a portion 77 of the camera bed plate near the center of the front thereof, and passes around pulleys 78 and 79 through an aperture 80 in a side member of the carriage, where it runs adjacent to the scale marked on the carriage so the graduations of the scale may be read thereby.

The tape passes longitudinally along the outer face of the carriage until it reaches a point near the rear thereof where it passes through an aperture 81 Fig. 40, in the carriage and around pulleys 82 and 83, thus passing transversely across the rear of the inside of the carriage to the opposite corner, where it passes around the pulley 83', supported by the bracket 84 from a frame portion 85 of the carriage, thence it passes forwardly along the carriage to the forward corner opposite the hand wheel 34, where it passes around a similar pulley, likewise carried by the carriage, and thence toward the bracket 76, Fig. 33, the free end 87 of the tape being connected to a spring 88, the other end of which is caught in the fixed end of the tape at 89.

It is apparent that, as the camera bed plate is moved transversely by the operation of the hand wheel 34, the tape will travel with it running over the pulleys, as heretofore described, and that the spring 88 will take up all of the slack and also allow for variations in temperature so the tape will be kept taut at all times.

These operations will be repeated until the printing plate has as many prints made thereon as is required in this particular horizontal line, then the printing plate will be moved upwardly or downwardly to a second vertical position and the series of operations repeated along a new horizontal line.

In locating the printing plate vertically, readings are taken from the micrometer 90, Fig. 2, and the micrometer and screws, controlled by the hand wheel 52, are of the same graduation and pitch as those just described, so the same accuracy is obtained on the vertical location of the printing plate as is obtained with the horizontal location of the negative. As the vertical movement of the screen frame which carries the printing plate has already been described, it will not be repeated at this place.

It is apparent that the entire plate may be filled with prints and that a record may be kept of the location of each print, so that, when a new printing plate is placed

over the pressure beam and a new negative placed on the negative holder, a similar set of prints may be made from the second negative so they will register exactly with those made from the first negative.

Means for releasing and readjusting the negative under its original contact pressure.

- 10 It is important that the same pressure be set up between the negative and the printing plate in making all of the prints, and special means have accordingly been provided for drawing the negative out of contact with the printing plate and bringing it back up against the printing plate in a new position with the same amount of pressure as existed between the negative and printing plate in its first position.
- 15 20 Looking at Figs. 16, 17 and 18, it will be seen that the camera plate 91 is mounted for longitudinal movement in the ways 92 and 93 of the camera bed plate 33, a gib 94 being provided to take up wear.
- 25 Journalled in the bed plate and bearing 95, supported on the carriage, is a shaft 96 to which eccentrics 97 and 98 are feather-keyed, so these eccentrics may be operated by the hand lever 99, keyed to the shaft 96, 30 regardless of the transverse position of the bed plate on the carriage.

As shown in Fig. 18, these eccentrics turn between lugs 100 and 101 of the camera plate, so the movement of the lever 99 moves the camera plate a certain distance forward or backward, a pin 102, Fig. 17, being provided to limit the throw in each direction so that a certain movement is always effected.

40 Accordingly the carriage may be moved forwardly by the hand wheel 10 so that the negative is brought into contact with the printing plate under a certain pressure with the lever 99 in its forward position. When 45 the lever 99 is thrown to its backward position, the negative is moved out of contact with the printing plate; the negative may then be moved to a new position, whereupon if the lever 99 is again thrown to its forward position the negative is brought into contact with the printing plate under the same pressure as it had in its first position.

It is important that the negative be always brought against the printing plate 55 with a considerable pressure and this pressure should be known. Accordingly provision is made for indicating the pressure exerted by the negative against the printing plate.

60 Looking at Figs. 2 and 61 it will be seen that the frame 148 is slidably mounted in the negative box and that cushion springs 230 are positioned between the frame 148 and the sub-frame 231 rigidly fastened to 65 the negative box.

It is apparent that a movement of the negative is thus allowed against the action of the springs 230.

Rotatably and slidably mounted in the frame 148 is one end 232 of a bell crank, 70 the crank of which is journalled at 233 in the wall of the negative box, the opposite end being fastened into an indicator 234 so that when the negative is pressed backwardly against the spring action this indicator 75 will be swung about an arc and the reading of the scale 235 will indicate the amount of pressure exerted by the negative on the printing plate.

80

Adjustable pressure beam and clamp bar for printing plates.

The printing plate on which the prints are to be made will be caught at its lower edge by clamps 103 carried by the frame clamp bar 51, Fig. 1, and will be caught at the upper edge by clamps 104, carried by movable clamp bar 105, Figs. 1 and 27.

Journalled in the frame clamp bar at 106 90 and 107, Fig. 25, and in the upper frame bar at 108 and 109, Fig. 1, are screws 110 and 111. Bevel gears 112 and 113 are interiorly threaded to co-operate with screws 110 and 111, respectively, and these bevel gears are actuated by bevel gears 114 and 115, respectively, driven by the shaft 116, and this shaft is rotated by the bevel gear 117, which in turn, is rotated by the bevel gear 118, and this bevel gear is provided 100 with a socket, 119, Fig. 27, so it may be rotated by applying a suitable wrench thereto through an aperture 120 in the movable clamp bar.

The movable clamp bar 105 is supported 105 by the bevel gears 112 and 113, which turn against the lower portion thereof so it is raised and lowered by the upward and downward travel of the bevel gears 112 and 113 on the screws 110 and 111, respectively.

By moving the clamp bar 105 upwardly, the printing plate is drawn taut across the face of the beam 59, whose adjustment has been heretofore described, and over a cushion pad to be hereinafter described.

It sometimes develops that, after a printing plate has been drawn as taut as possible by raising the clamp bar 105, there are small buckles in the plate which cannot be entirely taken out by an equal stretch of the entire plate. For this reason the clamps 104 are made individually adjustable.

Looking at Figs. 29 and 30, it will be seen that the clamp bodies 121 are hinged at 122 to the movable clamp bar 105, and when the printing plate 71 is caught in the jaws of the clamp at 124 by the action of the thumb screw 125 and it is necessary to take out a buckle of the plate under or adjacent to this clamp, the entire clamp may be raised 130.

in respect to the clamp bar 105 by turning the thumb screw 126, thus putting extra tension on that portion of the printing plate 71 adjacent to that particular clamp.

5 *Pressure beam cushion.*

If the negative is brought into contact with the printing plate against the contact pressure beam 59 under the pressure required for perfect contact, it will be practically impossible to make the negative strong enough to stand up without cracking, and it will, in fact, be commercially impossible to bring the negative and the printing plate into a perfect surface contact under such conditions. Accordingly, the contact pressure beam 59, Fig. 2, is provided with a cushion made up of a padding 134 over which is a rubberized blanket, 135.

20 This blanket is caught under the strap 136, screwed to the top of the contact beam 59, and is brought around and attached to the roller 137 having a socket 138 therein, the roller being journalled in the beam 59.

25 By means of a suitable wrench, this roller may be turned and the blanket 135 drawn tightly across the face of the beam, the dog 139 holding the roller in the position to which it has been drawn, thus maintaining the blanket 135 tightly across the face of the beam so the printing plate 71 may be stretched over the rubberized blanket.

When the negative 70 is brought into contact with the printing plate 71, the heavy pressure and cushion insures a perfect surface contact between the negative and the printing plate.

30 *Expansion of camera bed plate.*

40 As already explained, a heavy pressure is required between the negative and the printing plate, and for this reason the camera bed plate is mounted to the carriage by the dovetailed ways 42, so the bed plate can not tip under this contact pressure.

45 However, the center of the bed plate rides on the flat way 43', Fig. 1, and the rear end on the flat way 43, so that a close fit may be maintained in the dovetailed way at its forward end, while, at the same time, expansion of the bed plate may occur under changes of temperature without setting up any strains in the bed plate. A pair of braces 158, Fig. 2, may be bolted to the 50 camera plate and the negative holder to further stiffen the negative holder against the contact pressure.

55 *Joining the projection machine and printing plate holder in a unit structure during direct contact printing.*

60 A pair of heavy pins 140, Figs. 2, 7, and 8, are rigidly mounted on the carriage 3, one at each side thereof, and when the negative 65 is being brought into contact with the

printing plate, these pins register with sockets 141, one of which is carried by each of the braces 44.

When the proper pressure has been established, the lever 142 is thrown to its locking 70 position. This lever is keyed to the shaft 143, journalled in the housings of both of the sockets 141, and has keyed thereto eccentrics 144 so these eccentrics are brought down with a heavy pressure against their co-operating pins 140, as shown in Fig. 7, thus locking together the carriage and the printing plate holding frame under heavy contact and practically forming a unit structure of the two portions of the machine 75 while the print is being made.

80 *Reinforcement for the negative.*

As the negative is brought into contact with the printing plate under heavy pressure, it is necessary to reinforce the negative, which is ordinarily made of glass, and the means whereby this is accomplished is shown in Fig. 2.

85 The glass on which the negative film is placed, as designated by the numeral 70, Fig. 2, is supported by a heavy plate glass 145, this plate being, in my standardized machine, one inch in thickness.

90 A compressible gasket 146 is positioned between the negative and the walls of the negative box 147, and a heavy frame 148, passing about the interior of these walls, supports the plate glass 145, the movement being such that no pressure can be exerted 95 by the walls of the negative box 147 against the negative itself when the springs 230 are compressed.

95 *Maintaining focus of projection lamp.*

100 The projection lamp, which is of the ordinary type, is carried by the arms 150' of the supporting bar 150, Fig. 1. This bar is supported by standards 151 slidably mounted in the supports 153, Figs. 1 and 38.

105 The standards 151 have rack teeth 152 cut on the lower portions thereof co-acting with pinions 154, rotatable by the shaft 155, which has a hand wheel 156 rigidly fastened to one end thereof.

110 By turning the hand wheel 156 the bar 150, and hence the lamp carried thereby, may be raised or lowered, and, by means of the thumb nut 157, Figs. 37 and 39 the shaft 155 may be clamped, thus locking the lamp 115 in any desired position vertically.

115 *Telescoping mounting for lens, negative, condenser, and lamp holders.*

120 Mounted on the camera plate 91 are supports 159 for the lens holder, 160 for the negative holder, 161 for the condenser holder, and 153 for the lamp holder.

125 The lens holder 159 Figs. 16 and 17 is slidably mounted on the ways 165 and 166; the

negative holder is slidably mounted on the ways 163 and 164; the condenser holder is mounted on the ways 165 and 166, and the lamp holder on the ways 163 and 164, so the feet of the adjoining mountings can telescope, one with another, thus allowing a close positioning of the adjacent holders, while, at the same time, giving a strong, stable support to the mountings.

10 Bolts and nuts 167, sliding in the T slot 168, maintain the mountings in position on their ways.

In order to use negatives of different sizes to best advantage, I have three styles of negative boxes; namely, that style shown in Fig. 2 and designated by numeral 147; the style shown in Fig. 14 and designated by numeral 147', and the style shown in Fig. 15 and designated by numeral 147².

20 The style 147 is rectangular in structure, while the style 147' has the negative end smaller than the negative kit end, and the style 147² has the negative end larger than the kit end.

25 In all of the styles, however, the kit end is the same, so that the negative boxes are interchangeable in the kit 193 and the negative boxes are held therein by the spring clips 195, or other suitable means Fig. 60.

30 With the three different styles of negative boxes,—and the styles 147' and 147² may be made for any desired size of negative, all interchangeable in a negative kit—I am able to quickly change from one box to another and utilize a negative of any size to best advantage.

Centralizing the negative.

The negative holder mounting frame 169, Figs. 2, 45 and 59, has fastened thereto, by screws 170, a split ring comprised of half portions 171 and 172, the inner edge of the ring being bevelled, as shown at 173.

45 Encircling the split ring is a binding ring 174 which is split at the bottom and has two lugs at the adjacent ends 175 and 176, respectively; a screw 177 provides means for clamping this binding ring about the split ring.

50 Carried by the binding ring is a lug 178 adjacent to a lug 179, carried by the rotatable negative frame mounting 180.

It is evident that, if the screw 177 is loosened, the negative frame mounting may be rotated, together with the binding ring, through any desired number of degrees.

55 If the screw 177 is drawn up, then the only rotatable movement or angular adjustment that can be effected is through the action of the screw 181, Figs. 43, and 58 co-operating with nuts 182 and 183, pivotally mounted in the lugs 179 and 178, respectively, the latter adjustment being of the micrometer type for close work, and to facilitate reading of close, angular adjustment, one portion of the

outer surface of the split ring has vernier graduations thereon, as shown at 184, Fig. 44, reading with co-operating vernier graduations on a boss 185, carried by the negative frame mounting and lying in the same cylindrical surface as the outer edge of the split ring.

For vertical adjustment of a negative carried by the negative frame, the negative frame 186, Fig. 58, is slidably mounted in the negative frame holder 180 by its lugs 187 and 188, co-acting with ways carried by the lugs 189 and 190 of the negative frame holder.

A screw 202, journalled in the lug 203 of the negative frame mounting, co-acts, through thread engagement, with the lug 204, carried by the negative frame to control the vertical movement of the negative frame.

Guides 191 and 192 are carried by the negative frame 186, and slidably mounted therein is the negative kit 193, on which the negative 194 is placed and held thereto by spring clips 195, the frame 196 of the negative kit serving to position the negative therein.

This negative kit is mounted for transverse movement in the negative frame, and a lug 197, carried by the negative kit, Fig. 48, and lug 198, carried by the negative frame 186, are provided to co-operate with a screw 199 journalled in the lug 197 and threaded with the lug 198.

A micrometer dial 200 is provided to accurately measure the transverse movement of the negative. A similar dial 201, Fig. 46, is provided to indicate the vertical movements of the negative frame so that angular, vertical, and transverse movements of the negative may all be accurately measured.

The protractor 205, Fig. 49, is supported on pins 206 mounted in the negative holder mounting frame, and two sets of pins are provided, one of such length that the protractor may be hung just in front of the negative when the machine is used for direct contact printing, and the other of such length that the protractor may be hung adjacent to the negative when the machine is used for projection work.

In either case, the negative may be brought to a truly horizontal position by means of the spirit level 207, and it may also be lined up transversely by the scale 208, and it may be lined up angularly by the tongue 209 of the protractor.

Graduations 210 at the lower arc of the protractor, and graduations 211 and 212 at the two sides thereof, reading with graduations 213, provide accurate means for registering any desired variation from the horizontal or vertical, so that negatives that are slightly out of line with the horizontal or vertical may be registered, and co-oper-

ating color separation negatives may be lined up on the same angle by means of the protractor.

The tongue 209 is hinged at 214, and a 5 clamping screw 215 is provided for locking it in any desired position.

A straight edge 224 is slidably mounted on the tongue 209 for vertical adjustment thereon, and a clamping screw 225 is provided for locking it in any desired position 10 so that negatives may be lined up horizontally with the straight edge 224.

The tongue is provided with a scale 226, and the straight edge is also provided with 15 a scale 227, so that registration may be made at various points on the negative.

Means for daylight working of the machine.

20 It has been the general custom heretofore to operate machines of this general type in darkened rooms, as the exposure of the printing plate to daylight or artificial light for any considerable length of time would 25 cloud the plates and make it impossible to develop sharp, clean-cut prints thereon.

The advantages of being able to work a 30 machine of this kind in a light room are obvious, as the operator may be working continuously for a minimum of eight hours at a time.

It is self-evident that all that is required 35 in order to allow the operation of the machine in a light room is to prevent any light from reaching the printing plate except that light that comes from the projection machine.

I have, accordingly, provided curtains of 40 such style that, whether the machine is used for projection printing or contact printing, substantially all light except that coming from the projection machine is excluded from the printing plate.

As shown in Figs. 1, 54, 55, 56 and 57, curtains 216 and 217 are attached, by rollers 216' and 217' to the screen frame near the upper and lower clamp bars, and the free ends are caught at the upper and lower side 50 of the front of the bellows in slidable relation therewith.

Side curtains 218 and 219 are mounted on rollers 218' and 219' on the side members of the screen frame so as to lie snugly against the edges of the curtains 216 and 217 and 55 their free edges, which have rigid bindings 220 and 221 are attached at the front corners of the curtains 216 and 217.

By this means the camera may be slid 60 transversely without disturbing the curtains, and the screen frame may be raised or lowered without producing any openings between the four curtains described.

To close the open end of the boxlike 65 structure formed by the curtains, a curtain 222 is mounted on the roller 222' on the

front of the bellows, the free edge being fastened to the rigid edge of the curtain 220, and a similar curtain 223 runs from the other side of the camera to the rigid edge of the curtain 221, hence when the camera 70 is moved transversely, and the curtain 222 may be shortened, curtain 223 will be lengthened, and vice versa, all of the curtain rollers being provided with spring takeups.

When the machine is used for contact 75 printing, curtains 222 and 223 will be removed and the rigid bindings 220 and 221 of the curtains 218 and 219, respectively, are slidably attached to the sides of the front of the bellows so the printing plate is covered by curtains 216, 217, 218, and 219, except for that portion in front of the front member of the bellows, so that substantially all light is excluded from the printing plate except that coming from the lamp. 85

While I have described my invention and illustrated it in one particular design, I do not wish it understood that I limit myself to this construction, as it is evident that the application of the invention may 90 be varied in many ways within the scope of the following claims:

1. In a photo-lithograph machine the combination of a sub-base, longitudinal V tracks, one extending along each side of said 95 sub-base, a carriage, rollers supporting said carriage on said V tracks, the contact surface of said rollers being shaped to fit the sides of said V tracks, leaving the center of said rollers running free of the top of said 100 V tracks, supporting forks for each of said rollers, each side of said forks being threaded, and threaded bushings engaging with the threads of said fork to align said rollers on said tracks, said rollers being mounted 105 on shafts journaled in said bushings.

2. In a photo-lithograph machine the combination of a sub-base, a carriage mounted on said base, and slidably movable thereon longitudinally of said sub-base, gearing, including a screw, for moving said carriage longitudinally on said base, said gearing including a split nut co-operating with said screw, and means for dividing said split nut so that said carriage may be moved on said 110 sub-base manually without the operation of said gearing.

3. In a photo-lithograph machine the combination of a sub-base, a carriage mounted on said sub-base, by anti-friction rollers and movable longitudinally thereon, a hand wheel, a shaft rotated by said hand wheel, bevel gears rotated by said shaft, a second shaft rotated by said bevel gears, a train of spur gears rotated by said second named 120 shaft, a screw rotated by the last of the train of said spur gears and substantially centrally positioned in said carriage and extending longitudinally thereof, a split nut 125 housing carried by said sub-base, a split nut 130

- slidably mounted in said housing and adapted to engage with said screw when closed, whereby said carriage may be moved longitudinally by the rotation of said hand wheel, 5 an eccentric co-operating with each half of said split nut to open and close said split nut, and a link and lever mechanism including a lever mounted on said sub-base for operating said eccentrics.
10. 4. In a photo-lithograph machine the combination of a carriage, a camera bed plate mounted thereon for slidable transverse movement therewith, the forward end of said bed plate engaging with said carriage in a dovetailed shaped way, and a flat way supporting the rear end of said bed plate so the forward end of said bed plate may be slidable with a minimum of lost motion, while the bed plate may freely expand 15 under changes of temperature without distortion thereof.
5. In a photo-lithograph machine, the combination of a sub-base having tracks, each track with upwardly convergent side 20 walls and an upper wall connecting the convergent walls, a carriage, a plurality of rollers running on said tracks, the contact surface of each of said rollers being shaped to fit the sides of the tracks with the center 25 of the roller spaced from the upper walls of the tracks, and bearing devices on the carriage for rotatably mounting each roller thereon, said devices being capable of lateral adjustment, whereby the carriage is 30 supported for travel along the sub-base and aligned by lateral adjustment of the bearing 35 devices.
6. In a photo-lithograph machine, the combination of a sub-base having tracks, each track with upwardly convergent side 40 walls and an upper wall connecting the convergent walls, a carriage, a plurality of rollers, running on said tracks, and bearing devices on the carriage for rotatably mounting each roller thereon, said devices being capable of lateral adjustment, whereby the carriage is 45 supported for travel along the sub-base and aligned by lateral adjustment of the bearing devices.
50. 7. In a screen frame for a photo-lithograph machine the combination, with the screen members, of a movable clamp bar, means for raising and lowering said clamp bar in said screen frame, individual clamps 55 comprising a body portion and a jaw portion, said body portion being hinged to said clamp bar, and means for swinging said body portion with respect to said clamp bar.
8. In a screen frame for a photo-lithograph machine the combination of a lower clamp bar, means on said clamp bar for clamping one edge of a printing plate, an upper movable clamp bar, individual means carried by said movable clamp bar for gripping the upper edge of a printing plate,
- means for raising said movable clamp bar, thereby stretching the printing plate gripped by said upper and lower clamping means, and means for raising said individual clamping means with respect to said upper movable clamp bar to smooth out individual buckles from said plate. 70
9. In a photolithograph machine the combination of a screen frame guide, a screen frame mounted therein for vertical slidable movement therewith and having means thereon for carrying a printing plate, means for raising and lowering said screen frame, a contact pressure beam slidably mounted in said guide for vertical movement therewith, and independent means for raising and lowering said contact beam with respect to said guide and to said screen frame. 75
10. In a photo-lithograph machine the combination of a screen frame guide, braces for said guide, a screen frame mounted in said guide for vertical slidable movement therein, a movable clamp bar mounted on said screen frame for vertical movement therewith, a contact pressure beam slidably mounted in said guide for vertical movement therewith, and independent means for vertically moving said screen face, said clamp bar, and said contact beam. 80
11. In a photo-lithograph machine the combination of a sub-base, a carriage mounted for longitudinal movement thereon, a camera bed plate mounted for transverse movement on said carriage, a screen frame guide mounted on said sub-base, a screen frame slidably mounted in said screen frame guide and including a lower clamp bar for clamping the lower edge of a printing plate, an upper clamp bar movable vertically in said screen frame and having means thereon to clamp the upper edge of a printing plate, and a contact pressure beam mounted for vertical movement in said screen frame guide. 95
12. In a photo-lithograph machine the combination of a sub-base, a printing plate holding device vertically positioned on said sub-base, a carriage mounted on said sub-base for longitudinal movement thereon, a camera bed plate carried by said carriage for transverse movement thereon, a camera plate carried by said bed plate for longitudinal movement thereon, a carriage operating hand wheel on said carriage, instrumentalities actuated by said hand wheel whereby the rotation of said hand wheel will move said carriage longitudinally on said sub-base, means for rendering said instrumentalities ineffective so said carriage may be manually moved on said sub-base, a camera bed plate operating hand wheel, instrumentalities actuated by said last named hand wheel for moving said camera bed plate transversely on said carriage, and means for moving said camera plate longi- 100
- 110
- 115
- 120
- 125
- 130

tudinally in said camera bed plate through a predetermined distance.

13. In a photo-lithograph machine the combination of a sub-base, a printing plate holding device vertically positioned on said sub-base, a carriage mounted on said sub-base for longitudinal movement thereon, a camera bed plate carried by said carriage for transverse movement thereon, a camera plate carried by said bed plate for longitudinal movement thereon, a carriage operating hand wheel on said carriage, instrumentalities actuated by said hand wheel whereby the rotation of said hand wheel 15 will move said carriage longitudinally on said sub-base, means for rendering said instrumentalities ineffective so said carriage may be manually moved on said sub-base, a camera bed plate operating hand wheel, instrumentalities actuated by said last named hand wheel for moving said camera bed plate transversely on said carriage, and means for moving said camera plate longitudinally in said camera bed plate through 25 a predetermined distance, said means including a pair of lugs carried by said plate, an eccentric positioned between said lugs so that its rotation will move said plate longitudinally in said bed plate, a shaft 30 feather-keyed to said eccentric, and a hand lever for rotating said shaft.

14. In a photo-lithograph machine the combination of a sub-base, a printing plate holding device carried by the sub-base and 35 adapted to hold a sensitized printing plate in a vertical position, a main carriage mounted for travel on the sub-base toward and from the printing plate, a printing camera, means for supporting the camera on the 40 carriage for travel thereon toward and from the printing plate, mechanism operative on the camera supporting means for giving the camera a limited movement toward and from the printing plate whereby the camera 45 may be carried into contact with the printing plate after the main carriage has first been moved to carry the camera into close proximity to the printing plate.

15. In a photo-lithograph machine the combination of a carriage, a camera bed plate slidably mounted on said carriage, a 50 tape, having an indicating mark thereon, attached to said camera bed plate and extending through an aperture in a side member of said carriage and running longitudinally along the outside of said side member and through a second aperture therein, anti-friction devices for supporting said tape so that, when said bed plate is moved 55 on said carriage, said tape will travel along the side member thereof, and a scale on the side member of said carriage for reading the distance which said camera bed plate has moved on said carriage.

16. In a photo-lithograph machine the

combination of a carriage, a camera bed plate mounted on said carriage for transverse movement thereon, a tape, having an indicating mark thereon, one end of said tape being attached to said bed plate; anti-friction devices around which said tape passes so that a portion of said tape extends longitudinally along one side member of said carriage, the free end of said tape being attached to said bed plate through a resilient connection, whereby said tape is kept taut regardless of expansion or contraction. 70

17. In a photo-lithograph machine the combination of a carriage, a camera bed plate slidably mounted thereon for transverse movement thereon, a tape, one end of which is attached to said bed plate; anti-friction supporting means for said tape positioned adjacent to an aperture in a side member of said carriage; a second anti-friction supporting device for said tape positioned adjacent to a second aperture in said side member of said carriage near the opposite end thereof; a third anti-friction supporting device supported by said carriage and positioned transversely across said carriage from said second named aperture; and a fourth anti-friction device positioned substantially transversely across said carriage from said first named aperture, said tape passing through said apertures and over said anti-friction devices, and resilient means connecting the free end of said tape with said bed plate. 80

18. In a photo-lithograph machine the combination of a sub-base, a carriage mounted for slidable longitudinal movement thereon, a camera bed plate mounted for slidable transverse movement on said carriage, a camera carried by the bed plate, a vertical printing plate holding device mounted on said sub-base and toward and from which the carriage moves on the sub-base, a hand wheel carried by said carriage, instrumentalities actuated by said hand wheel for moving said bed plate transversely on said carriage; a micrometer for measuring said transverse movement, said micrometer having minute graduations thereon; a tape and indicating scale co-acting with said carriage and said bed plate for roughly indicating the transverse movements of said bed plate, a vertically positioned adjustable printing plate holder carried by said printing plate holding device; a hand wheel, instrumentalities actuated by said hand wheel for vertically moving said printing plate holder, and a micrometer, having minute graduations thereon, for indicating the vertical movements of a printing plate carried by said holder. 100

19. In a photo-lithograph machine the combination of a carriage, a camera bed plate mounted for transverse slidable movement on said carriage, a tape co-operating 105

- with said bed plate and said carriage for indicating approximately, by a scale on said carriage, the transverse movement of said bed plate; a hand wheel, instrumentalities actuated by said hand wheel for moving said bed plate transversely on said carriage, a micrometer also actuated by said hand wheel for accurately and minutely indicating the transverse movement of said bed plate on said carriage so that a movement thereof may be roughly checked by said tape and accurately checked by said micrometer.
20. In a photo-lithograph machine the combination of a carriage, a camera bed plate mounted for transverse slidable movement on said carriage, a tape co-operating with said bed plate and said carriage for indicating approximately, by a scale on said carriage, the transverse movement of said bed plate; a hand wheel, instrumentalities actuated by said hand wheel for moving said bed plate transversely on said carriage, a micrometer also actuated by said hand wheel for accurately and minutely indicating the transverse movement of said bed plate on said carriage so that a movement thereof may be roughly checked by said tape and accurately checked by said micrometer; a cyclometer giving an indicating reading, one for each revolution of said hand wheel, for checking the revolutions thereof and, through said check, indicating movements of said bed plate.
21. In a photo-lithograph machine the combination of a sub-base, a printing plate holding device supported by said sub-base, a carriage longitudinally movable on said sub-base, a negative holder, means for supporting said negative holder on said carriage, means for bringing a negative held by said negative holder into a pressure contact against a printing plate carried by said printing plate holding device, means for supporting a negative in said negative holder against pressure between the negative and the printing plate, means for indicating the pressure of said contact between said negative and said printing plate.
22. In a photo-lithograph machine the combination of a printing plate holding device, a negative holder, means for bringing a negative held by said negative holder into pressure contact with the printing plate held by said printing plate holding device, means for indicating pressure between said negative and said printing plate, and a lever for bringing said negative out of contact with said printing plate and returning said negative into contact with said printing plate under the same pressure as was the first contact therewith.
23. In a photo-lithograph machine the combination of a sub-base, a printing plate holding device carried by said sub-base, a carriage mounted for longitudinal movement on said sub-base, a camera plate, means for supporting said camera plate on said carriage for slidable longitudinal movement therewith, a negative holder carried by said camera plate, means for bringing a negative held by said negative holder into a surface pressure contact with a printing plate held by said printing plate holding device through the longitudinal movement of said carriage on said sub-base, and means for effecting a longitudinal movement between said camera plate and said carriage whereby said negative may be brought away from contact with said printing plate and returned into the same pressure contact with said printing plate.
24. In a photo-lithograph machine the combination of a sub-base, a printing plate holding device carried by said sub-base, a carriage mounted for longitudinal movement on said sub-base, a camera bed plate mounted for transverse movement on said carriage, a camera plate mounted for longitudinal movement on said bed plate, a negative holder carried by said camera plate, means for moving said carriage longitudinally on said sub-base and thereby bringing a negative held by said negative holder into a pressure contact with a printing plate held by said printing plate holding device; means for indicating the pressure thus set up; means for moving said camera plate in said bed plate backwardly to draw the negative from contact with said printing plate, said movement being predetermined so that, when said negative is again brought into contact with said printing plate, pressure therebetween will be the same as the original pressure contact.
25. In a printing plate holding device for a photo-lithograph machine the combination of means for stretching a printing plate, a pressure beam behind a printing plate so stretched, a padding on the face of said pressure beam, a blanket, one edge of which is fastened to one edge of said pressure beam, a roller carried by the other end of said pressure beam, said blanket passing across the face of said pressure beam and being attached to said roller so it may be drawn tightly against the padding over the face of said pressure beam by the rotation of said roller, and means for locking said roller.
26. In a printing plate holding device for a photo-lithograph machine the combination of a screen frame, a clamp bar carried by said screen frame and having means thereon to clamp the lower edge of a printing plate, a movable clamp bar carried by said screen frame and having means thereon to clamp the opposite edge of a printing plate, means for moving said movable clamp bar in said screen frame, a movable pressure beam so positioned as to be just behind a printing plate held by said clamp bar, a blanket pass-

ing across the face of said pressure beam, and means for drawing said blanket taut thereover.

27. In a photo-lithograph machine the combination of a sub-base, a printing plate holding device, a support, instrumentalities carried by the support for making direct contact prints on a printing plate carried by said printing plate holding device, said support and holding device being mounted on said sub-base for relative movement toward and from one another, and means for locking together said printing plate holding device and the support into a substantially rigid unit structure for the direct contact printing operation.

28. In a photo-lithograph machine the combination of a sub-base, a printing plate holding device carried by the sub-base, a carriage mounted on said sub-base for movement thereon toward and from the holding device, and means for locking said printing plate holding device and said carriage together into a substantially rigid unitary structure.

29. In a photo-lithograph machine the combination of a sub-base, a printing plate holding device mounted on said sub-base, a carriage mounted for movement on said sub-base toward and from the holding device, a negative holder supported by said carriage so that a negative held thereby may be brought into direct contact with a printing plate held by said printing plate holding device, and means for locking said carriage and said printing plate holding device into a substantially rigid unitary structure with said negative and said printing plate under pressure contact.

40 30. In a photo-lithograph machine the combination of a sub-base, a printing plate holding device mounted thereon, a socket carried by said printing plate holding device, a carriage mounted on said sub-base for longitudinal movement therewith, a pin mounted on said carriage and adapted to engage with said socket, and means for locking said pin in said socket.

50 31. In a photo-lithograph machine the combination of a sub-base, a printing plate holding device mounted thereon, a socket carried by said printing plate holding device, a carriage mounted on said sub-base for longitudinal movement therewith, a pin mounted on said carriage and adapted to engage with said socket, and means for locking said pin in said socket, said means including an eccentric adapted to impinge on said pin, and a lever for rotating said eccentric.

60 32. In a photo-lithograph machine the combination of a sub-base, a printing plate holding device, a carriage mounted for longitudinal movement on said sub-base, a camera bed plate mounted for transverse movement on said carriage, a camera plate

mounted for longitudinal movement on said camera bed plate, a negative holder mounted on said camera plate so a negative held thereby may be brought into direct surface contact with a printing plate carried by said printing plate holding device; means for locking said carriage to said printing plate holding device in a substantially rigid unitary structure with a pressure contact between said negative and said printing plate, and means for bringing said negative out of contact with said printing plate a predetermined distance and returning said negative into contact with said printing plate under the same pressure.

70 33. In a photo-lithograph machine the combination of a sub-base, a printing plate holding device, a carriage mounted for longitudinal movement on said sub-base, a camera bed plate mounted for transverse movement on said carriage, a camera plate mounted for longitudinal movement on said camera bed plate, a negative holder mounted on said camera plate so a negative held thereby may be brought into direct surface contact with a printing plate carried by said printing plate holding device; means for locking said carriage to said printing plate holding device in a substantially rigid unitary structure with a pressure contact between said negative and said printing plate, and means for bringing said negative out of contact with said printing plate a predetermined distance and returning said negative into contact with said printing plate under the same pressure.

80 34. In a photo-lithograph machine the combination of a sub-base, a printing plate holding device carried by said sub-base, a carriage mounted for longitudinal movement on said sub-base, a camera bed plate mounted for transverse movement on said carriage, a camera plate mounted for longitudinal movement on said camera bed plate, a negative holder carried by said camera plate, means for moving said carriage toward said printing plate holding device and bringing a negative held by said negative holder into a pressure surface contact with a printing plate held by said printing plate holding device; means for locking said printing plate holding device into a substantially rigid unitary structure with said carriage; means for moving said camera plate longitudinally on said camera bed plate, thereby drawing said negative out of contact with said printing plate; means for moving said camera bed plate transversely on said carriage so that said camera plate may be moved, through its longitudinal movement operating means, toward said printing plate holding device, said camera plate traveling a certain predetermined distance so that said negative may be brought

- into contact with said printing plate in a new position thereon under the same pressure as was exerted therebetween in its original position thereon.
35. In a photo-lithograph machine the combination of a camera plate, a negative holder positioned thereon and slidably engageable therewith, and a detachable brace of the character described and cooperatively arranged between said negative holder and said camera plate to withstand pressure exerted against a negative carried by said negative holder.
36. In a photo-lithograph machine, a device for mounting a printing plate upon which a plurality of prints are to be made, a camera, means for producing relative movement between the camera and said device toward and from one another and also in a direction parallel to the printing plate in order to make a number of separate prints successively on the printing plate, and extensible enclosing means connected between the camera and said device for enclosing the printing face of the printing plate to exclude light therefrom except that received from the camera, said enclosing means comprising a plurality of spring roller curtains which automatically remain taut during the movements of the camera.
37. In a photo-lithograph machine the combination of a screen frame, photo printing means associated therewith and including a bellows, curtains mounted horizontally in association with said screen frame on spring take up rollers, means for connecting the free edges of said curtains with said bellows, vertically positioned screens mounted on spring take up rollers associated with said screen frame, the free edges of said vertical curtains being attached to the free corners of said first named curtains; a second pair of vertically disposed curtains mounted on said bellows with spring take up rollers, the free edges of said last named curtains being joined with the free edges of said first named vertical curtains.
38. In a photo-lithograph machine the combination of a screen frame having means for holding a printing plate therein, a negative holder associated therewith and adapted to be brought into contact with a printing plate held by said screen frame at various positions thereon, curtains extending from the upper and lower portions of said screen frame to the upper and lower portions of said negative holder, curtains extending from the two sides of said screen frame to the vertical edges of said negative holder, spring roller take ups for said curtains, and slidable connections between said curtains and said negative holder.
39. In a photo-lithograph machine the combination of means for supporting a printing plate against pressure, means for making a photo print on said printing plate including a negative, a transparent reinforcement for said negative, means for creating pressure between said negative and the printing plate on said printing plate supporting means, and means for indicating pressure so set up.
40. In a photo-lithograph machine the combination of a sub-base, a screen frame guide carried by said sub-base, a screen frame carried by said screen frame guide and having means therein to receive a printing plate, backing means for said printing plate to withstand pressure brought against said printing plate; a carriage mounted for longitudinal movement on said sub-base, photo printing means, including a negative, mounted on said carriage, means for moving said photo printing means transversely of said carriage, means for moving said carriage on said sub-base to bring a negative held by said negative holder into a pressure contact with a printing plate carried by said frame, and means for rendering said last named means ineffective so said carriage may be manually moved.
41. In a photo-lithograph machine, a sub-base member, a carriage member mounted for travel along said sub-base member, a screw mounted for rotation on one of the members and extending in the direction of relative travel between said members, a split nut carried by the other of said members and operable into and out of threaded engagement with the screw so as to couple the members through the screw and split nut or uncouple them and permit relative travel of the members, means for operating the split nut into or out of coupled relation with the screw, and means for rotating the screw to propel one member relatively to the other when the split nut is coupled to the screw.
42. In a photo-lithograph machine, a sub-base member, a carriage member mounted for travel along the sub-base member, a screw mounted for rotation on one of the members and extending in the direction of relative travel between said members, a housing carried by the other of said members through which the screw extends, a split nut slidable in said housing into and out of threaded engagement with the screw, mechanism for rotating the screw to cause relative travel between the members when the nut is coupled to the screw, an eccentric operating the split nut into and out of engagement with the screw, and means for operating the eccentric.
43. In a photo-lithograph machine, a carriage member, a camera bed plate member slidable laterally of the carriage, one of the members having at one end a rail with which the other member engages so that the bed plate member will be guided thereby in its

lateral travel, the members at the opposite ends having flat way contact surfaces whereby the plate member will be guided in a definite path by the rail member and the members can freely expand and contract without binding or distortion.

44. In a photo-lithograph machine the combination of a sub-base, a printing plate holding device carried by the sub-base and adapted to hold a sensitized printing plate in a vertical position, a main carriage mounted for travel on the sub-base toward and from the printing plate, an auxiliary carriage mounted on the main carriage for travel thereon laterally of the direction of travel of the main carriage, a printing camera, a support for said camera mounted on the auxiliary carriage for travel thereon in a direction parallel with the direction of travel on the main carriage on the sub-base, mechanism for giving the camera support a limited movement on the auxiliary carriage to carry the camera into contact with the printing plate after the main carriage has first been moved to carry the camera into closed proximity to the printing plate.

45. In a photo-lithograph machine the combination of a sub-base, a printing plate holding device carried by the sub-base and adapted to hold a sensitized printing plate in a vertical position, a main carriage mounted for travel on the sub-base toward and from the printing plate, a printing camera, means for supporting the camera for travel on the sub-base toward and from the printing plate, and auxiliary means for giving the camera a limited movement toward and from the printing plate, whereby the camera may be carried into contact with the printing plate by operation of the auxiliary means after the supporting means has been moved to carry the camera into close proximity to the printing plate.

46. In a photo-lithograph machine the combination of a sub-base, a printing plate holding device carried by the sub-base and adapted to hold a sensitized printing plate in a vertical position, a main carriage mounted for travel on the sub-base toward and from the printing plate, a printing camera, means for supporting the camera on the carriage for travel thereon toward and from the printing plate, and means including an eccentric cam for giving the camera a limited movement toward and from the printed plate whereby the camera may be carried into contact with the printing plate after the main carriage has been moved to carry the camera into close proximity to the printing plate.

47. In a photo-lithograph machine, the combination of a sub-base, a printing plate holding device carried by the sub-base and adapted to mount a printing plate in a ver-

tical plane, a main carriage movable on the sub-base toward and from the screen, an auxiliary carriage mounted on the main carriage for movement in a direction parallel with the plane of the printing plate, a tape connected to the auxiliary carriage and running over guides on the main carriage whereby the tape will always move concomitantly with the auxiliary carriage, said tape and main carriage having a scale and reference mark cooperating to indicate the positions of the auxiliary carriage and the exact distances traveled by it on the main carriage, and a camera carried by the auxiliary carriage.

48. In a photo-lithograph machine, a base, a printing plate holding device carried by the base, a main carriage mounted on the base for movement toward and from the plate holding device, an auxiliary carriage mounted on the main carriage for movement in a direction transverse to the direction of travel of the main carriage on said base, a tape connected at its ends to one of the carriages, extending therefrom in opposite directions which are the directions of travel of the auxiliary carriage on the main carriage, guide devices on the other of the carriages over which the tape is guided to the other side of its connection to said one of the carriages, the tape and said other of the carriages having a scale and reference mark cooperating together to indicate the positions of the auxiliary carriage on the main carriage and the exact distances traveled by it on the main carriage, the connection between one end of the tape and said one of the carriages having therein a resilient element for keeping the tape taut under all temperature conditions, and a camera carried by the auxiliary carriage.

49. In a photo-lithograph machine the combination of a sub-base, a carriage mounted for slidable longitudinal movement thereon, a camera bed plate mounted for slidable transverse movement on said carriage, a camera carried by the bed plate, a vertical printing plate holding device mounted on said sub-base and toward and from which the carriage moves on the sub-base, a hand wheel carried by said carriage, instrumentalities actuated by said hand wheel for moving said bed plate transversely on said carriage; a micrometer for measuring said transverse movement, said micrometer having minute graduations thereon, and a tape and indicating scale co-acting with said carriage and said bed plate for roughly indicating the transverse movements of said bed plate.

50. In a photo-lithograph machine the combination of a sub-base, a screen frame guide, a screen frame carried by the guide for movement thereon, means for operating the screen frame in its guide, a micrometer

device for indicating accurately the travel of the frame, a camera, and means for supporting the camera on the sub-base in position to print successively upon a light sensitive plate held by said frame, the frame being shifted through an increment of movement between successive exposures so as to produce a plurality of prints upon the plate, the distances between which may be accurately determined by the micrometer device.

51. In a photo-lithograph machine, the combination of a sub-base, a printing plate holding device carried by said sub-base, a carriage mounted for movement on said sub-base, toward and from the holding device, a camera plate, means for supporting said camera plate on said carriage for limited movement thereon toward and from the holding device, a negative holder carried by said camera plate, and means for shifting the camera plate on the carriage into and out of surface pressure contact with a printing plate held by said printing plate holding device, after the negative has first been moved into close proximity to the printing plate by movement of the carriage on the sub-base.

52. In a photo-lithograph machine, the combination of two relatively movable parts, one of which constitutes a support for a light sensitive plate, a camera, a support for the camera carried by the other of the parts for limited movement thereon toward and from the plate support, and means including a shaft and an eccentric cam thereon for causing said limited movement in either direction upon rotation of the shaft whereby after relative movement between the parts has brought the camera and light sensitive plate into proximity to one another, the shaft may be operated to bring the camera into contact with the light sensitive plate.

53. The machine substantially as set forth in claim 52, and means for indicating the pressure set up between the sensitive plate and the camera.

54. In a photo-lithograph machine, a sub-base, two parts carried thereby for relative movement toward and from one another, one of the parts having means to mount a sensitized printing plate, a camera carried by the other of the parts, one of the parts having a locking pin and the other a socket into which the pin extends when the parts are brought into close proximity to one another, and means carried by the part with the socket for locking the pin therein.

55. The machine substantially as set forth in claim 54, in which the locking means includes an eccentric cam which may be rotated into contact at its periphery with the

pin, and means for rotating the cam to lock or unlock the pin.

56. In a photo-lithograph machine, the combination of a sub-base, two parts carried by the base one of which is movable toward and from the other on the sub-base, means for locking the parts together as a rigid structure after they have been brought into close proximity to one another on the sub-base, one of the parts having thereon means for supporting a printing plate holding device, the other of the parts having an element movable thereon in a direction transverse to the direction of relative travel between the parts, a second element mounted on the first element for movement thereon in a direction toward and from the plate holding device, means for moving the second element toward or from the plate holding device, means on the second element for supporting a photographic negative in a position parallel with a printing plate held by the holding device, whereby when the parts are locked together the negative will be in close proximity to the printing plate and the second element may be operated to carry the negative into and out of pressure contact with the printing plate, the transverse movement of the first element enabling movement of the negative laterally into a position adjacent an unexposed portion of the printing plate, so that another movement of the negative into contact with the printing plate will enable the making of another print thereon from the negative.

57. In a photo-lithograph machine, a base, a frame on said base, a support for a sensitized printing plate adjustable in said frame for moving the printing plate in its own plane in one direction, a backing member adjustable behind the plate into positions to receive pressure applied to the plate at the opposite face thereof, an element mounted on the base facing toward the plate, a second element movable on the first element in a direction parallel with the plane of the plate, a camera plate mounted on the second element for movement toward and from the printing plate, a camera mounted on the camera plate for movement therewith into contact with the printing plate, and means for shifting the camera plate to carry the camera into pressure contact with the printing plate.

58. The machine substantially as set forth in claim 57 in which the frame and first element may have relative movement on the base to bring the camera and printing plate into close proximity to one another preparatory to shifting the camera into contact with the printing plate.

HERMAN C. BOEDICKER.
